UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

APPARATUS FOR MINING COAL.

Application filed July 5, 1913, Serial No. 777,436. Renewed November 27, 1925.

- My invention relates to improvements in apparatus for mining coal and other materials, and one of the objects of my invention is to provide an improved and simplified apparatus for mining coal and other materials, which will be effective, efficient, reliable and rapid in operation.
- Further objects of my invention will appear hereinafter.
- Referring to the accompanying drawings: Figure 1 illustrates a general view and elevation of a mining machine embodying my invention.
- Figure 2 is a general top plan view of the mining machine shown in Figure 1.
- Figure 2^a is a cross section on the line 2^a—2^a of Figure 2.
- Figure 3 is a view partly in section substantially on the line 3—3 of Figure 1, showing the details of the truck and the mechanism by which various adjustments and movements are imparted to this mechanism.
- Figure 4 is a vertical sectional view substantially on the line 4—4 of Figures 2 and 10, illustrating the adaptability of the parts to the position of the cutting mechanism in various levels.
- Figure 5 is a detail view of a rolling mill joint used between the cutter heads and the driving mechanism therefor.
- Figures 6 and 7 are detail views of the parts by which the cutting mechanism may be removably attached to the driving mechanism.
- Figure 8 is an enlarged sectional view on line 8—8 of Figure 2, illustrating the details of one of the yielding cushions to prevent the binding of the cutting mechanisms while the cut is being made.
- Figure 9 is an enlarged vertical view substantially on the line 9—9 of Figures 2 and 10, this view being partly in section and illustrating details of the balancing supports for the cutting mechanism.
- Figure 10 is a sectional view substantially on the line 10—10 of Figures 1 and 9.
- Figure 11 is a longitudinal sectional view on the line 11—11 of Figures 2 and 12, illustrating the details of the oscillating or reciprocating vertical cutter.
- Figure 12 is a sectional view of this mechanism on the line 12—12 of Figure 11.
- Figure 13 is a detail fragmentary sectional view on the line 13—13 of Figure 2.
- Figures 14 and 15 are views in elevation and plan, respectively, of the modified cutting mechanism embodying my invention.
- Figure 14^a is a transverse detail sectional view on the line 14^a—14^a of Figure 14.
- Figure 16 is a detail sectional view on the line 16—16 of Figure 14.
- Figure 17 is a detail of several of the links of one of the cutting chains.
- Figure 18 is a view in diagram illustrating a vein or seam of coal into which a plurality of kerfs have been cut in accordance with my improved method.
- Figure 19 is also a diagrammatic view in the direction in which the cutting operations rests in the vein or seam of coal.
- Figure 20 is a diagrammatic sectional view of the vertical kerfs on the line 20—20 of Figure 19.
- Figure 21 is a similar diagrammatic sectional view on the line 21—21 of Figure 19.
- In the mining of coal it is particularly desirable to cut the coal into large, regular and uniform blocks so that not only may they be conveniently removed from the mine and packed for transportation but the coal in large blocks will retain its efficiency much better than if broken into comparatively small particles. In the drawings, and particularly in Figures 18 to 21 inclusive, I have diagrammatically illustrated my improved method by which the coal may be cut into large blocks and by which these desirable results may be readily obtained.
- Referring to these figures, *a* indicates a vein or seam of coal which may be representative of any vein or seam from which coal is to be mined. These figures show the operations in the progress of running an entry into the vein. I cut a plurality of kerfs into the vein or seam a substantial distance in accordance with the requirements and conditions of the particular vein which is to be mined. As shown in the drawings, these kerfs lie in planes disposed at angles with respect to each other so that the coal will be divided up into a plurality of blocks of convenient and practicable size. The horizontal kerfs *B* lie preferably in substantially horizontal planes with respect to the pitch or lie of the vein and preferably extend from one side of the room to the other. These kerfs also extend into the vein longitudinally whatever distance is found to be practicable under the particular conditions. In the diagram in Figure 18 the horizontal

planes in which these kerfs B are cut are preferably parallel and arranged one above the other, and there may be as many of such kerfs as the conditions require. In the diagram I have illustrated three horizontal kerfs, one along the upper line of cleavage or roof of the room, one along the lower line of cleavage or floor of the mine, and one intermediate the upper and lower ones and preferably equally spaced therefrom. The thickness of the vein and the size of the blocks to be removed obviously determines the number of such kerfs to be made. The vertical kerfs C preferably lie in substantially vertical planes at approximately right angles to the horizontal kerfs and are spaced apart at intervals across the width of the room. These vertical kerfs may extend into the vein any desired distance but the best results are obtained by extending them slightly beyond the inner edges of the horizontal kerfs, as illustrated more clearly in the dotted lines in Figures 18 and 21 and in full lines in Figure 20. While the vertical kerfs C may be cut so that they will intersect the horizontal kerfs, if desired, and thereby completely separate the blocks of coal, I find it desirable to leave small uncut portions C' adjacent the horizontal kerfs, particularly when the vertical kerfs are cut first and a kerf-cutting or mining machine is used in making all the kerfs. These uncut portions, although relatively thin, serve to hold the blocks against lateral displacement when the strain comes on them during the cutting of the horizontal kerfs. That is to say, as the cutting of the horizontal kerfs progresses from one side of the room to the other the strains or pressure exerted by the cutting mechanism along the line of the horizontal kerfs will not operate to break the blocks loose and move them laterally even though the vertical kerfs C are already cut, for the reason that the uncut portions C' serve to hold the blocks in position against this lateral pressure. The uncut portions C' do not resist to any appreciable extent the breaking loose of the blocks and the movement of them in a substantially vertical direction when the blocks drop or break loose by reason of their own weight or when, as in some cases, a slight force is found to be necessary to dislodge them. In addition to the vertical kerfs C I also cut a continuous vertical kerf D in the rear of the horizontal kerfs B and the vertical kerfs C. The number of these vertical kerfs D depends upon the number of horizontal kerfs B which are cut. In the drawings, I have shown three horizontal kerfs, as previously described, and in consequence I cut only one kerf D between the upper and lower horizontal kerfs B. The kerf D, as will be noted, lies in a general plane which is substantially transverse to the planes of both the horizontal kerfs B and the vertical kerfs C. In the drawings I have shown it as intersecting the intermediate horizontal kerf B and all of the vertical kerfs C. The kerf D preferably does not extend either upwardly or downwardly far enough to intersect the upper and lower horizontal kerfs B but stops short of these last mentioned kerfs. This leaves the uncut portion D¹ along the rear ends of the blocks and the purpose of the kerf D is simply to weaken the portions or ends of the blocks which are attached to the body of the vein so that the blocks may be readily broken loose from the body of the vein, either by the force of their own weight, which will cause them to drop downwardly, or by reason of a slight additional force, if such additional force is found to be necessary. In the drawings I have shown the end portions D² of the kerf D and the end portions of the horizontal kerf B as being cut upon a curve or arc but it is to be understood that this is not necessary and that the end portions of the said kerfs may be given in any configuration desired. These arc-shaped ends, however, are of advantage where certain types of mining machines, such as I will hereinafter describe, are used, for the reason that it enables the cutting mechanism to start into the vein at the front ends or front portions of the wall of material, and these arc-shaped end portions also serve to determine the width of the room and to form the side walls thereof. In carrying out my improved method I prefer to cut the vertical kerfs C first, as previously mentioned, and then cut the horizontal kerfs B and the vertical kerfs D. The horizontal kerfs B may be cut simultaneously and the vertical kerfs D may also be cut at this time. In cutting the kerfs B and D I prefer to start the cutting mechanism into the vein substantially at the point D³ at one side of the room and carry on the cutting operation gradually from this point across the vein to the other side of the room. As the cutting of the kerfs B and D progresses across the vein there is a tendency for the blocks thus formed to drop of their own weight, but to prevent these blocks from dropping, and binding the cutting mechanism, I support the blocks in their position until at least the cutting mechanism has passed each block. The blocks may be supported in any desired manner and the supports may be left in place, if desired, until all of the blocks in the kerfs have been cut or the supports may be removed as soon as the cutting mechanism passes the vertical kerfs C and the block allowed to drop one by one. In the machine which I have illustrated in the drawings and which I will hereinafter describe, I provide a support for the blocks which trails along in the kerfs immediately following the cutting mechanism and temporarily supports the blocks in which the kerfs have been cut beyond said blocks, this supporting mechanism gradually moving from under the blocks and allowing them to drop if the condition of the coal is such that

they will break loose of their own weight, or at least leaving the blocks in such condition that they may be broken loose by the application of a slight force.

5 Referring now to Figures 1 to 17, inclusive, I will describe my improved mining machine. As shown in the drawings, the entire machine is mounted upon a suitable truck E having wheels 1 so that it may travel along suitable 10 rails or tracks 2 laid in the mine room or entry. These wheels 1 are mounted upon axles 3 having journals in the truck frame E and each axle carries a beveled gear 4. A shaft 5 extends longitudinally of the truck 15 and carries at its end the beveled gears 6, which mesh with the beveled gears 4, and through the medium of which and the shaft the truck may be propelled along the track. One of the gears 4 is disposed at one side of 20 the shaft 5 and the other beveled gear 4 is disposed at the opposite side of the shaft so that the shaft will rotate both sets of wheels in the same direction, and power will thus be applied to all of the wheels of the truck 25 so that the tractive effort will be distributed on all the wheels. One of the wheels of each pair is provided with a brake-shoe 7 (Figure 3) hinged or pivoted at 8 to the truck frame E and adapted to be operated by means of the 30 links 9 which connect to the brake-shoes and to a lever 10 centrally pivoted upon a depending bracket 11 on the frame E. This lever has an upstanding arm or handle 12 by which it may be rotated to throw the brake- 35 shoes into and out of engagement with the wheels and thereby break or release the wheels, as desired.

In order to lock the truck to the track and at the same time permit the truck to 40 travel along the track I provide another set of angularly disposed flanged wheels or rollers 13, the flanges of which, as shown in Figure 1, engage the under side of the ball of the rails 2 and thereby prevent the truck 45 from being tilted or raised relatively to the track by any strains or undue loads which may come upon the machine and which might have a tendency to over-balance it. These locking wheels or rollers 13 are mounted at 50 the lower ends of the depending arms 14, which arms are rotatably mounted upon short studs 15 outstanding from the frame of the truck so that the locking wheels may be swung inwardly away from the tracks to release the 55 truck from the tracks in the event that it is desired to do so on such an occasion as when the machine is to be taken out of the mine or the tracks relaid in other parts of the mine. The bearing portions of these rotary arms 14 60 have gear-teeth 16 which mesh with and are driven by worms 17, the worms 17 being mounted upon the ends of short shafts 18. The shafts 18 are journaled in bearings 19 on the truck frame and carry hand-wheels 20 by which they may be operated. This con- 65 struction permits the locking wheels to be readily thrown out of engagement with the tracks and at the same time the worm gearing serves to lock the arms in any position to which they are rotated. The truck frame 70 E is, as shown in the drawings, in the form of a flat platform which has an upstanding annular rim or flange 21 of comparatively large diameter. The various parts of the driving and cutting mechanism are primarily supported upon a broad flat platform 25 which has an underhung parallel or sub-platform 26 rigidly fastened thereto. This sub-platform 26 has a depending annular flange or rim 27 similar to the upstanding flange 21 75 on the truck. The flange 27 is of such diameter that it telescopes within the flange 21 and the two together, in conjunction with the platform 25, constitute a turn-table, the two flanges 21 and 27 being relatively rotatable. 80 At the same time these flanges constructed in this manner permit the main platform 25 to be raised and lowered with respect to the truck frame E so that the mechanism may be adjusted to various heights. The truck 85 platform E carries a large bushing or member E¹ rotatably mounted therein and centrally disposed with respect to the flanges 21 and 27. This bushing has an annular arm or shoulder E² which holds it in position against 90 the upper side of the truck platform. The bushing projects through the truck platform and on its lower end has a collar E³ provided with worm gear teeth on its periphery, and this collar is driven to rotate the bushing by 95 means of a worm E⁴, which is mounted upon a shaft E⁵ journaled in a bearing depending from the platform. The shaft E⁵ has a hand-wheel by which it may be rotated. The sub-platform 26 (Figure 3) rests upon and is supported by a large nut E⁶. This nut is screw-threaded on its interior and is threaded upon a hollow upstanding portion E⁷ of the rotary bushing E¹. Thus by manipulating the hand-wheel on shaft E⁵ the bushing E¹ 100 may be rotated in either direction and the rotation of this bushing causes the threaded upstanding portion E⁷ thereof to screw into or out of the large nut E⁶ thereby raising and lowering the platform or turn-table 25. In order to lock the large nut E⁶ 105 against rotation it has a depending pin E⁸ which slides in an opening in the truck frame E. A motor M is mounted upon the platform 25 at one side thereof so as to assist 110 in balancing the machine against the weight of the cutting mechanism, which is in general disposed at the opposite side of the platform. This motor-shaft, as shown more clearly in Figures 1 and 2, carries a pinion 28 upon its 115 end, which pinion drives a large gear 28^a which is mounted upon a shaft 29 supported in bearing standards 30 on the platform. The shaft 29 carries a pinion 31, which pinion drives a train of gears 32 and 33. The shaft 120 125 130

29 may be said to constitute the main shaft of the machine and from it the various mechanisms are driven, the gears 28 and 28^a being of proper ratio to properly reduce the speed 5 of the motor. The gear 33 is comparatively large in diameter and is mounted upon a counter-shaft 34 (see also Figures 11 and 12), which counter-shaft is journaled in bearing standards 35 rising from the platform 10 25. The intermediate gear 32 of the train is mounted upon a shaft which is suitably journaled in a bearing 36 mounted upon the platform 25 and is merely an idler interposed in the train for the purpose of securing the proper direction of rotation of the counter-shaft 34, as will hereinafter appear. The counter-shaft 34 carries two beveled gears 37, which are rotatably mounted upon the shaft 34 and which mesh with a similar beveled gear 38 interposed between them. The beveled gears 37 may be connected with or disconnected from the shaft 34 by means of an intermediate two-way clutch member 39 so that the shaft 34 may be arranged to drive either of these 15 20 25 gears. The clutch mechanism may be of any suitable kind for the purpose. In the drawings I have shown the clutch member 39 as being a longitudinally slid able sleeve feathered to the shaft to rotate therewith, and being adapted to be shifted longitudinally in either direction by means of a hand-lever 40. Thus by shifting the clutch member 39 into engagement with either one of the gears 37 the latter may be connected with the shaft 34 to be driven thereby. The gears 37 and clutch member 39 have corresponding teeth for interlocking the two together. The purpose of this arrangement is to permit the shaft 42, upon which the gear 38 is mounted, to be 30 35 40 driven in either direction. This shaft 42 is mounted in a bearing 43 rising from the platform 25 and it carries a beveled gear 44 at its other end which drives a similar beveled gear 45, which latter gear is mounted upon a vertical shaft 46 journaled in a bearing outstanding from the platform 25. The shaft 46 projects below the platform 25 and carries at its lower end a pinion 47 which meshes with and drives a large spur gear 48 disposed between the platform 25 and its sub-platform 26 (Figure 2). The large gear 48 is mounted upon the upper end of a vertical shaft 49 which is journaled at its upper end portion in the sub-platform 26. The shaft 49 is disposed in the center of the telescoping flanges 21 and 27. Below its upper bearing the shaft 49 is preferably square in cross section and is adapted to slide vertically within a correspondingly square-holed bushing 50. The bushing 50, however, is rotatably journaled in the rotary bushing E² so that a sliding bearing is thus formed for the lower end portion of the shaft 49 permitting the shaft to adapt itself to the various positions to which the platform 25 is raised or lowered 45 50 55 60 65 70 75 80 85 90 95 100 105 110 115 120 125 130

with respect to the truck. The shaft 49, however, on account of its being squared with respect to the bushing 50, will drive the bushing at any position in which the shaft is adjusted. The bushing 50 has a beveled gear 51 on its lower end which meshes with and drives a similar gear 52 on the shaft 5 beneath the truck, which shaft transmits power, as before described, through the beveled gears 4 and 6 to the wheels of the truck. By this construction it will be seen that the power of the motor is transmitted through the various shaft clutches of the gears above described to the wheels 1 of the truck to propel the truck along the track, the direction of movement of the truck along the track being controlled, as above intimated, by the clutch member 39 which is positioned intermediate the beveled gears 37 on the counter-shaft 34. It will be noted, however, that since the large horizontal gear 48 is carried, generally speaking, by the truck, and the pinion 47, which meshes with this large gear, is carried, generally speaking, by the rotary platform or turn-table 25, there is a tendency for the pinion 47 to "walk around" the large gear 48 instead of actually rotating or driving the large gear, providing that the resistance offered by the wheels to the movement of the truck along the track is greater than that which is offered by the platform 25 to rotary movement about its axis. In other words, if the truck offers greater resistance to being propelled along the track than the platform 25 does to being rotated, the pinion 47 will travel around the large gear 48 and thereby rotate the platform, rather than actually rotate the large gear itself to propel the truck along the tracks. I utilize this very condition for intentionally rotating the platform or turn-table on its axis by simply setting the brakes 7 (Fig. 3) against the wheels and thereby, in a sense, locking the truck to the track. This has the effect then of practically locking the large gear 48 against rotation, and in consequence when the pinion 47 is driven it will travel around the periphery of the large gear 48 and the platform will thereby be given a rotary movement. This condition of the mechanism also holds good in the other way; that is to say, if the resistance offered by the platform or turn-table to being rotated is greater than offered by the truck to being propelled along the track the result will be that the large gear 48 will be actually rotated by the pinion 47, and the resultant power will be applied to propel the truck along the tracks. In order, therefore, to insure the resistance to rotary movement of the platform being the greater I provide means by which I may positively lock the platform against rotation upon the truck frame. Figure 1 shows a boss 53 projecting from the side of the flange 21. This boss is screw-threaded and carries a pin 54 which 130

may be screwed into or out of any one of a series of elongated openings 55 distributed around the inner flange 27. This pin has a hand-wheel 56 at its outer end by which it 5 may be manipulated. This pin, in conjunction with the holes or openings 55, serves to lock the two flanges against relative rotation and thus lock the platform against rotation. This pin may be withdrawn from whichever 10 opening 55 it happens to have been inserted into, by turning the hand-wheel 56 when it is desired to rotate the platform or turn-table. Upstanding from the platform or turn-table 25 is a pair of bearings 60 in which is journaled a shaft 61. This shaft carries, and is 15 driven by a gear 62 which meshes with a gear 63 on the counter-shaft 34. A capstan or winding drum 64 is rotatably mounted upon the shaft 61 and is adapted to be connected 20 with or disconnected from the shaft by means of a sliding clutch member 65 having teeth 66 arranged to interlock with corresponding teeth at one end. The clutch member 65 may be readily shifted by means of a hand-lever 25 67. The winding drum may be used independently of the previously described truck propelling mechanism or it may be used in conjunction therewith where the resistance offered to the cutting mechanism is too great 30 to be overcome by the tractive effort of the truck wheels alone. The manner in which this winding drum may be used is to anchor a cable 68 at a point 69 in the mine distant from the machine and winding the cable upon 35 the drum. The cable may be anchored at any point in the mine, and in conjunction with the winding drum may be used to pull the machine along its tracks whether the said tracks be laid in curves or in a straight line, as is 40 the usual practice in mining operations.

The platform 25 carries at one side thereof a rigid upstanding casing or member 70 which forms a guideway and supporting member for two vertically reciprocable or 45 slidable members 71, 72 which are bifurcated so as to leave an open space 73 (Fig. 9) between their respective bifurcations. These reciprocable members 71, 72 support the upper and lower cutting mechanisms at their 50 upper and lower ends respectively, and by reason of their vertical slidability the cutting mechanisms may be raised and lowered to vary the height of the mine room. In order to reduce to a minimum the power required for reciprocating the members to adjust the cutting mechanisms, I arrange the mechanism so that the weight of the upper cutting mechanism will assist in raising the lower cutting mechanism and one of the bifurcations of each of the members 71, 72 are 55 provided with gear teeth 74 and 75 to form racks, the two sets of teeth or racks being disposed on opposite sides of the opening 73, as clearly shown in Figures 9 and 10.

Between the two racks and meshing there- 60 with is a broad-faced pinion or gear 76, the hub portions of which are rotatably journaled in the upstanding guide member 70, as shown in Figure 10, so that these journals will take the entire weight of the cutting mechanisms. At one end, the hub member 77 of the pinion 76 is provided with a worm gear 78 which is driven by a worm 79; the worm 79 being mounted upon a shaft 80 which is journaled in a bracket 81 on the 65 guideway member 70 and which has at its outer end a handwheel 82 for the convenient manipulation thereof. It will thus be seen that by rotating the hand-wheel the pinion 76 may be rotated and the members 71 and 72 reciprocated vertically relatively to each other and to the pinion 76. It will be particularly noted, also, that the weight of the member 71 and the cutting mechanisms mounted thereon in moving downward will assist in rotating the pinion 76 and cause the pinion to exert, 70 through the rack 75, a lifting action upon the member 72, or vice versa, when the cutting mechanisms are to be adjusted farther apart the weight of the member 72 and its cutting mechanism, in moving downward, will assist in rotating the pinion through the medium of the rack 75 and the pinion will in turn operate upon the rack 74 to assist in raising the member 71 and its cutting mechanism. Thus it will be seen that the weights of the members 71 and 72 and their cutting mechanisms counteract each other and very little power will be required to rotate the pinion to adjust the cutting mechanisms any desired distance apart. It will be noted also that the worm gearings 78 and 79 serve as an automatic locking mechanism to hold the parts in any position to which they are adjusted. The pinion 76 and its hub 77 are 75 hollow and form a bearing for the main shaft 29 which extends through its brackets beyond the hub and carries at its outer end a beveled pinion 83. It will be noted, however, that the shaft 29 is relieved of the weight of the cutting mechanisms since this weight is taken up by the bearings for the hub 77 in the guideway member 70. The pinion 83 meshes with and drives a large horizontally disposed beveled gear 84 (Figures 1, 2, 4 and 10), which gear 84 is carried by and preferably formed integrally with an elongated sleeve 85 and it is through this mechanism that the driving power is transmitted to the cutting mechanisms. The sleeve 85 is journaled in the bearings 86 which are formed in an extension 87 of the main platform 25. This sleeve carries a removable collar 88 at its lower end which normally prevents it from being shifted upwardly out of its bearings, and the gear 84 forms a collar for this same purpose at the upper end of the sleeve. This sleeve is adapted to drive the two shafts 89 and is hollowed for its entire length so as 80 to form a rolling mill joint for the ends 85 90

of the shafts 89, as clearly shown in Figure 4. The rolling mill joint between the shafts 89 and the sleeve 85 permits a universal movement of said shafts to take care of any 5 inequalities which would be likely to bind the shafts in the event that they were rigidly mounted in the sleeve 85, and they also permit the shafts to move vertically in the sleeve 85 to accommodate the raising and lowering 10 of the upper and lower cutting mechanisms. These rolling mill joints also permit the upper and lower cutting mechanisms to be slightly inclined upwardly or downwardly, as will be later explained. In the machine 15 shown in the drawings I provide three sets of cutting mechanisms, an upper and a lower one and an intermediate one. These cutting mechanisms are in the form of flat elongated bars comparatively thin and arranged to cut 20 relatively thin kerfs. Each cutter bar or cutting mechanism has an elongated flat frame around the periphery of which the cutting chain travels. The frames of the cutting mechanisms each comprises two main 25 parts or members 95 and 96. The members 96 of these frames form guideways for offset extensions 97 on the members 95 so that the members 95 and 96 may be adjusted longitudinally relatively to each other for the 30 purpose of tightening or loosening the cutting chains, as desired (Figures 1, 2, 4, and 13). The off-set extensions 97 are in the form of slotted tail pieces which embrace a fixed block 98 on the member 96, which block 35 is positioned in the slot of the tail piece and has two threaded bars 99 extending longitudinally of the slot in opposite directions. These threaded bars extend through the end portions 100 of the tail pieces 97 and each 40 carries at its outer end a nut 101. This mechanism forms a convenient and simple means by which the frame members of the cutting mechanism may be adjusted relatively to each other to tighten or loosen the chain. 45 Each of the central blocks 98 has journaled therein a shaft 102 which has keyed to its upper end a sprocket wheel 103 around which the cutter chain lies and by which the cutting chain is driven. These shafts 102 are 50 carried upon cup-shaped members 104 which are hollow and arranged to form rolling mill joints in conjunction with the other ends 105 of the shafts 89 so that there is universal driving connections between the shafts 89 55 and the shafts 102. The cup-shaped members 104 are journaled in members 106 extending from the frame members 96. The frame members 96 are supported in cup-shaped members 107 and the connections between the members 106 and 107 are preferably in the form of bayonet joints so that the upper and lower cutting mechanisms may be bodily removed from their supports in the event that it is desired to replace them or 60 remove any of their parts. These bayonet joints, as will be seen, are formed by providing the cup-shaped members 106 with laterally extending segmental flanges 108 which are adapted to engage in the undercut grooves 109 in the cup-shaped supports 70 107 (see Figures 4, 6 and 7), the rims of the cup-shaped supports 107 being provided with cut-away portions or notches 110 to permit the insertion or removal of the flanges 108. It will thus be seen that by entering the 75 flanges 108 in the notches 110 and rotating the cup-shaped member 106 a portion of a turn the cutting mechanism may be removably attached to the supports 107. The rims of the cup-shaped supports 107 have cams 80 111 adjacent the notches 110 and these cams are adapted to act upon the segmental flanges 108 to force the two members tightly together. The direction of rotation necessary to fasten the cutting mechanisms in place 85 by these bayonet joints is opposite to that in which they rotate with the platform 25 so that the cutting operations will act to tightly set the cutting mechanisms in position on their supports. It is desirable, in a 90 machine of this character, that the cutting mechanisms be capable of being inclined slightly with respect to their supports so that they may be accurately adjusted and to this end I have other supporting members 95 107 upon the ends of the levers or arms 112. These arms or levers, as will be noticed more particularly in Figures 1 and 9, are pivoted at 113 in lateral extensions 114 of the 100 vertically reciprocable members 71 and 72, and the other ends of the levers or arms 112 are formed as segmental gears 115 which mesh with worms 116. These worms 116 are mounted upon shafts in the ends of the members 71 and 72 and these shafts are provided with hand-wheels 117 so that by manipulating the hand-wheels 117 the arms 112 may be rocked about their pivots to vary the angular position of the cutting mechanisms. The adjusting mechanism for the lower cutters 110 differs from that of the upper ones only in the fact that the lever 112 is formed as a bell-crank lever so that the hand-wheel 117 and the worm which it drives may be brought up away from the floor of the mine and thus 115 not interfere with the cutting mechanism. The cutting chains need no particular description except to say that they travel around the periphery of the frame member 96, and are provided with side links 118 to 120 guide them on their frame and prevent the chains from becoming displaced. Each chain has a series of cutters or cutting tools 119 spaced at intervals. The intermediate cutting mechanism is similar to the upper and 125 lower cutting mechanism except that it is not attached to its support by bayonet joints. It has, however, similar means to the upper and lower cutting mechanisms for tightening and loosening the chain, and the description 130

thereof need not be repeated. Its parts 96 and 97, as shown in Figure 4, are wider than the corresponding parts of the upper and lower cutting mechanism so as to allow room 5 for the driving sleeve 85, as clearly shown in Fig. 4. This intermediate cutting mechanism also is not intended to be inclined or adjusted at different angles as is the case of the other cutting mechanisms.

- 10 In order to support the blocks and to prevent them from settling upon and binding the cutters while the kerfs are being cut, I provide some of the cutter bars with a number of separators or yielding devices distributed 15 at different points in the surface of the cutter mechanisms. In the present case I employ two of these devices for the cutter bars. These devices, as will be seen more clearly by reference to Figures 2 and 8, are 20 in the form of two telescoping shells or cups 125, 126 between the bottoms of and within each of which is a spiral spring 127 which constantly urges the two cups or shells apart; that is, urges the devices to expand. These 25 devices are set into suitable openings in the cutting mechanism frame members 96 and when expanded they are somewhat thicker than the thickness of the cutting mechanism and particularly the cutter frame member 30 96, as clearly shown in Figure 8. The outer cup members are provided with annular flanges or arms 128 at each end thereof which engage with corresponding shoulders 129 formed in the openings of the cutter bar 95 35 to prevent the devices from becoming displaced with respect to the cutter bar. The end surfaces 130 of the cups 125 and 126, it will be noted, project beyond the surfaces of the cutter bar frame 95 so that these 40 devices will hold off the blocks of coal from the cutter bar frame and allow the cutter mechanism to travel unrestrictedly in the kerfs. The shoulders 129 are so arranged with respect to the flanges 128 that the cutter 45 bar may have some movement relatively to the separator devices to allow for inequalities in the kerfs. It will be noted that the end surfaces of the cups 125 and 126 are pressed against the opposing faces of the 50 upper and lower blocks of coal and thus keep the blocks spread apart for the free passage of the cutter mechanism but the cups 125 and 126 are, by reason of the spring 127, yieldable with respect to each other which allow 55 them any variations in the thickness of the kerfs. The lower cup member 126 has a central instanding boss 131 supporting a threaded bolt 132 which passes up through the bottom of a socket or depression 133 60 formed in the end of the upper cup member 125 and this bolt carries a nut. The purpose of this arrangement is to regulate the distance to which the spring 127 may expand the cup members 125 and 126 so that the devices 65 may be adjusted to the particular distances

and requirements. It will be noted that only the intermediate and lower cutter bar mechanisms require these separator devices for the reason that these cutter mechanisms have blocks of coal above them. The upper cutter mechanism, however, does not require these separators because they operate along the roof of the mine and the roof of the mine 70 supports itself.

So far I have described only the cutter mechanism for cutting the horizontal kerfs. However, I intend that the cutting of the rear vertical kerf D, previously described, shall be done simultaneously with the cutting of the horizontal kerfs, and in consequence I provide the machine with mechanism for this purpose. Where the rear vertical kerfs are of such character that they are not intended to reach all the way to the upper and lower 75 horizontal kerfs to completely sever the blocks of coal at their rear ends, I utilize a cutter wheel, such as indicated at 140 in Figures 1, 2, 11 and 12, but where the rear vertical kerf D is to be made wide or high 80 enough to intersect the upper and lower horizontal kerfs and completely sever the blocks from the body of the vein, the structure shown in modification in Figures 14 and 15 85 may be used to better advantage, the reason for this being that in the latter case a cutter wheel 140 of sufficiently large diameter to completely sever the rear ends of the blocks would be too bulky and inconvenient to handle, especially when the curves D² (Figure 90 95 18) at the ends of the kerf are to be made. The cutter wheel 140 is, as seen clearly in Figures 11 and 12, mounted upon and driven by a horizontal shaft 141 which projects beyond the extension 87 of the platform 25 to a point substantially in line with the outer 100 ends of the horizontal cutter bars or mechanisms. This shaft is journaled at its ends in bearings 142 in a flat elongated casing 143 which is mounted upon the platform extension 87. The vertical cutter 140 operates in 105 a flat plane of rotation and since its position is such that it will not freely operate to cut the curves D² (Figure 18) at the ends of the vertical kerf D, it is necessary, in order that the cutter 140 may freely move in the curved 110 portion D² of the kerf, that the carved end portions D² of the kerf be considerably thicker than the normal cutting width of the blades or knives 140^a of the cutter 140. For 115 these reasons I make provision so that the cutter wheel 140 may be given an oscillating movement so that it will cut a thicker kerf than the normal thickness of the cutter wheel, and to this end I mount the elongated casing 143 in guideways 144 on the platform extension 87 so that this casing may be reciprocated longitudinally and thereby oscillate or 120 reciprocate the cutter wheel 140. In order that the shaft 141 may be rotated or driven 125 during the oscillating movement of itself and 130

the casing and cutter wheel I key the large gear 33 upon the end of the counter-shaft 34 and I extend the hub 34^a of this gear and provide it with a square bore 34^b into which the correspondingly squared end portion 141^a of the shaft 141 is inserted. Thus the shaft 141 may be given a reciprocating movement and it will, at the same time, be driven by the counter-shaft 34. It will be realized that on account of the large diameter of the cutter wheel 140, the cutting knives or tools 140^a on the periphery of the wheel are somewhat removed from the driving shaft 141 and on account of the great leverage thus created the torsional strain on the central shaft 141 will be considerable, and perhaps objectionable. To preclude any possibility of the shaft or parts from breaking under the cutting strains I provide a supplemental driving mechanism for the cutter wheel which will exert its power upon the cutting wheel close to the periphery thereof. In the present machine this supplemental driving mechanism is preferably in the form of two additional shafts 145 disposed within the casing 143 and parallel with but spaced from the central shaft 141. These shafts are journaled in bearings 146 at the ends of the casing 143 so that they will oscillate with the central shaft. The cutter wheel 140 is made hollow and its inner periphery provided with gear teeth 147 to form a hollow gear, and the outer ends of the supplemental shafts 145 carry gears 148 which mesh with the teeth 147 and thereby drive the cutter wheel at points adjacent its outer or cutting periphery. Referring to Figure 12, it will be seen that the large gear 33 is also made hollow and formed as a hollow gear and this hollow gear drives the supplemental shafts 145 by means of the gears 149 carried by the inner ends of the shafts 145. The gear teeth 150 of the hollow gear 33 are, as will be noticed, of considerable length so that the gears 149 may remain in mesh and be driven thereby during the oscillation of the shafts. The shafts 141 and 145 all lie in the same plane, and the casing 143, which preferably completely encloses the shafts, is made as flat and thin as is necessary to completely enter and move in the intermediate horizontal kerfs, and if desired, this casing may also be provided with a number of yielding separator devices K, such as previously described in connection with the horizontal cutter mechanisms. It will be observed that the oscillating movement of the vertical cutter 140 is not really necessary during the time that this cutter is operating in a straight line, and I prefer, therefore, that the oscillating movement of the cutter be subject to the control of the operator so that he may start and stop this oscillating movement as required. In the machine shown in the drawings I obtain this control as follows: The hub 34^a of gear 33 has a pinion 152 formed at its outer end,

and as seen in Figures 2 and 11, this pinion drives a larger gear 153 positioned above it and mounted upon a shaft 154. One end of this shaft is suitably journaled in a bearing standard 155 rising from the platform extension 87 and the other end is journaled in a horizontal bearing bracket 156 mounted at the side of the platform extension. This shaft 154 carries a cam 157 for oscillating the casing 143, and spaced from this cam is a disc or flat collar 158 which, in conjunction with the control boss hereinafter described, operates to hold the casing 143 against oscillation. The casing 143 carries a roller 159 which is positioned between the cam 157 and the collar 158. On the casing 143 is a relatively slideable member or bar 160 which may be readily shifted by the handle 161 and which carries spaced rollers 162 and 163. This sliding bar 160 is intended to be shifted to either of two positions, depending upon whether the cutter is to be oscillated or to remain still, and it may be locked to the casing in either of its positions by means of a removable plug or pin 164 which passes through an opening in the slide-bar 160 and is adapted to enter one of two openings 165 in the casing according to whichever position the bar is shifted to. When the bar 160 is placed in the position in which it is shown in Figure 11, it will be noted that the collar 158 is confined between the two rollers 159 and 163, and since the plane of this collar is transverse to the axis of the shaft 154 no oscillating movement will be imparted to the casing 143 and the cutter. However, this position of the bar 160 and roller 162, as is clearly seen, will not be affected by the cam 157, but when the bar 160 is shifted to the right so as to bring the roller 162 closer to the roller 159 the cam 157 will be confined between said two rollers and will impart an oscillating movement to the casing and cutter. It will be noted that when the oscillating movement is stopped by shifting the sliding bar 160 by the lever the cutter wheel will always stop at the outer end of its oscillating stroke so that it will be in a proper position to continue its cutting in a straight line from the moment that it leaves the curve and is also ready to start the other curve the moment it is thrown into oscillating movement.

The conditions and grades of coal, as is readily understood, varies in the different veins or mines. The coal in some veins is more likely to break loose of its own weight than in other mines, consequently in operating a machine of this character in some grades of coal the coal is likely to drop immediately behind the cutters and perhaps tend to bind the cutter mechanism. As a protection, therefore, I provide an additional support which trails immediately behind the vertical cutter 140 and the lower horizontal cutter mechanism. This support is preferably constructed

as a lever which is suitably pivoted at 170 upon a stud outstanding from the platform extension 87. The arm 171 of this lever is long enough to extend almost to the ends of the cutter mechanism and is preferably in the form of a broad flat plate, as shown clearly in Figures 2 and 2^a, which is preferably slightly thinner than the thickness of the cutter mechanisms. This supporting plate is positioned to follow immediately behind the cutter mechanisms and to thereby support the coal immediately after the cutting mechanisms have passed. In order that this supporting plate may yield to the inequalities of the kerfs and at the same time be sufficiently rigid to properly support the coal above it, the aforesaid lever has a short arm 172 upon which a stiff spiral spring 173 presses, thereby tending to raise the plate 171 upwardly. This spring 173 is confined between the end of the lever arm 172 and the head 174 of a vertical bolt 175. This bolt passes through a lug 176 outstanding from the platform extension 87, and carries a nut 177 at its end by which the tension of the spring may be regulated, as desired. I have described the supporting device which is associated with the intermediate cutter mechanism, and hence it is mounted upon the platform extension 87 and is positioned immediately behind the casing 143 which carries the vertical cutter 140. The lower supporting device, which is associated with the lower horizontal kerf cutting mechanism, is identical in all respects to the one above described, and the description thereof need not be repeated except to say that it is mounted upon the member 96 of the cutter mechanism frame.

It may be desirable, under some conditions, to cut the vertical kerfs D all the way to the upper and lower horizontal kerfs so as to completely sever or separate the blocks of coal from the body of the vein, and in Figures 14 to 17 I have illustrated the modified mechanism embodying my invention and adapted for the purpose of cutting the rear vertical kerfs D to completely sever the blocks from the body of the vein. I have illustrated, and will describe, this mechanism as operating in conjunction with the above described horizontal kerf cutting mechanisms to completely sever the blocks on all sides but it will be observed that this modified mechanism is of such construction that it may be used by itself to cut, not only the rear vertical kerf D, but also the horizontal kerfs all in the same operation. It is possible, however, that if this mechanism were relied upon entirely for cutting all of the kerfs in exceptionally hard material the strains upon it might be too great, and this is one of the reasons why I prefer to use it in conjunction with the above described horizontal kerf cutting mechanism when very hard material is to be cut. Referring to Figures 14 to 17, it will be observed

that the three horizontal kerf cutting mechanisms are in general the same as those above described so far as their construction, operation and adjustment are concerned. Some of the details have been slightly modified so that the machine may be adapted to the mounting of the modified vertical kerf cutting mechanism. For instance, it will be noted that the upper and lower horizontal kerf cutting mechanisms are mounted directly upon the lateral extensions 114 of the vertically reciprocating members 71 and 72 instead of being mounted upon the pivoted arms 112 for adjustment. The hand-wheel 82 and the parts which it operates to raise and lower the upper and lower horizontal kerf cutting mechanisms is disposed, as seen in Figure 15, upon the other side of the guideway casing 70 but its operation is the same. The main shaft 29 carries a large beveled pinion 200 which drives a similar gear 201 mounted upon a transverse counter-shaft 202 which is journaled in bearings 203, two of the bearings 203 being formed in large massive arms 204 which incline upwardly from the platform extension 87 and which, as will later appear, are arranged to support the vertical kerf cutting mechanism frame. The counter-shaft 202 carries a pinion 205 at its other end which, through the medium of the gears 206, 207 and 208 and the short shaft 209, drive the counter-shaft 34 from which shaft, as above described, the various propelling movements of the truck and the rotary movements of the platform are accomplished in the same manner. The platform extension 87 supports two large rectangular loop-shaped frames U and L around the peripheries of which cutting chains 210 and 211 operate. These frames, as will be noticed, lie in substantially vertical planes but the plane of the lower frame is in advance of the upper frame in the direction of movement of the cutting mechanisms. The lower reach or side of the upper frame and the upper reach or side of the lower frame are coincident with each other in a horizontal plane, as will be seen in Figure 14, so that they will both enter and move in the intermediate horizontal kerf which has already been cut or which may be cut by the chain 211 where the horizontal kerf cutting mechanisms are not used. The upper reach of the upper frame and the lower reach of the lower frame are coincident with the upper and lower horizontal kerf cutting mechanisms respectively so that they may travel or move in the upper and lower horizontal kerfs cut by said horizontal kerf cutting mechanisms or in the upper and lower horizontal kerfs made by the chains 210 and 211 where the upper and lower horizontal kerf cutting mechanisms are dispensed with. The upper frame U has an extension or arm 212 and this extension 212 forms a horizontal guideway for a horizontal extension 213 on the arm 204, previously men-

tioned, and these relatively sliding parts 212 and 213 support the frame U in such manner that it may be shifted bodily horizontally to properly adjust it in this direction. The 5 lower frame is also equipped with a similar extension 214 which forms a similar guideway for the horizontal portion 216 of the other arm 204, above mentioned. These constructions permit the frames U and L to be bodily 10 adjusted horizontally, and in order that this adjustment may be conveniently accomplished it will be seen that the guideway extensions 212 have slot or openings 217 in their faces and outstanding lugs 128 at their ends. 15 The horizontal portions 213 and 216 of the arms 204 have outstanding lugs 219 which move in the openings 217. The lugs 219 have openings through which adjusting bolts 220 pass and these bolts carry nuts 221 and 222 20 on each side of the lugs 219 so that by manipulating the nuts the frames U and L may be adjusted horizontally and secured firmly in their adjusted positions.

The frames U and L are preferably made 25 each in two sections so that they may be readily contracted or expanded in a vertical direction to properly align with respect to the kerfs and the horizontal kerf cutting mechanisms. The inner vertical reaches 225 of one 30 of the sections of each frame is formed as a bar and these bars 225 are adapted to telescope with or slide vertically in the vertical guides 226 of the other section of each frame, as clearly shown in Figures 14 and 16, and 35 the vertical guides 226 are provided with slots or openings 227 which accommodate lugs 228 movable therein and mounted upon the flat vertical bars 225. The vertical guides 226 having corresponding lugs 229, and these lugs 40 carry adjusting bolts 230 and adjusting nuts 231 which are similar to the bolts and nuts previously described, for obtaining the horizontal adjustment of the frames. The outer ends or vertical reaches 233 and 234, 45 respectively, of the sections of the two frames also telescope with each other, as shown clearly in Figure 14^a, which is a section on the line 14^a—14^a of Figure 14. No adjusting parts are required at the outer ends of the 50 frames since the adjusting bolts 230 and nuts 231 at the inner ends of the frames are sufficient, as seen clearly in Figures 14—14^a and 15. The upper, lower and outer end reaches or sides of the frames U and L have grooves 55 formed therein and in these grooves the cutting chains 210 and 211 are adapted to travel, the corners of the frames and the grooves therein being preferably rounded, as shown in Figure 14, so that the chain will travel 60 freely. The chains may be constructed by means of the side links 235 and intermediate or center links 236 suitably connected together by the hinge 237. It will be noted, however, that the center links 236 have lugs 65 237 outstanding laterally from said links and

preferably formed integrally therewith. These lugs project beyond the faces of the side links 235 and are provided with suitable sockets into which the cutting tools 238 may be inserted, the tools being secured in said 70 sockets by means of set-screws 239 (Figure 17). Thus it will be seen that although the chains travel in the usual manner of operating chains of this character, the cutting parts 238 project from beyond the grooves 75 in the frames in which said chains run. In other words, the cutting portions or parts 238 of the chains are disposed laterally or on the faces, so to speak, of the frame U and L, and when these frames are swung or moved 80 in a horizontal direction they will cut horizontal kerfs where the horizontal kerf cutting mechanism, above described, is dispensed with, or they will move freely in the horizontal kerfs if such kerfs have already been 85 cut by the above described horizontal kerf cutting mechanism. When the cutting frames U and L and the above described horizontal kerf cutting mechanisms are used in 90 conjunction with each other, and this is my preference, it will be seen that the cutting frames U and L will not be subjected to the strains of cutting horizontal kerfs as these kerfs will have already been cut by the horizontal kerf cutting mechanisms. The only 95 cutting strains then to which the frames U and L will be subjected will be that which is necessary to cut inner vertical kerfs D. In other words, only the vertical portions or 100 outer ends of the frames and the corresponding reaches of the cutting chain will be subjected to cutting strains, which is comparatively small. This construction has an advantage over a single chain operating in only 105 the upper and lower horizontal kerfs and to cut a single vertical kerf D extending between the upper and lower horizontal kerf, this advantage being obvious because the cutting strains are divided up between the 110 two cutting chains 210 in the present construction.

Any suitable mechanism may be employed 115 for driving the chains 210 and 211. In the drawings I have shown the chains as being looped around and being driven by two sprocket wheels 240 (Figure 14). These 120 sprocket wheels are mounted upon the shafts 241 and 242. The shaft 241 is journaled at one end in a bearing 243 formed at the point where the extension 213 joins the supporting arm 204, and at its other end in a bearing 244 rising from the platform extension 87. The lower shaft 242 is journaled in a single bearing 245 which is formed at the point where the extension 216 joins the lower supporting arm 204. These two shafts receive power 125 from the counter-shaft 202 by means of suitable gearing; the shaft 241 having a large gear 246 which is driven by a gear 247 on the counter-shaft 202. The lower shaft 242 car- 130

ries a similar large gear 248 which is driven by the gear 205 on the counter-shaft 202. It will be noted that this driving arrangement is such that the chains 210 and 211 travel in the same direction, as shown by the arrows in Figures 14. The lower reach of the upper chain 210 and the upper reach of the lower chain 211, being coincident with each other, necessarily travel in opposite directions in the intermediate horizontal kerf, but this obviously is not objectionable because they are not cutting. I find it advisable, under certain conditions, to employ the supporting plates 171 to operate in the intermediate and lower horizontal kerfs, and in Figure 15 I have indicated these devices in dotted outline so that they are preferably positioned immediately behind the cutting frames U and L. They are identical in construction with those described in connection with the previous construction and the frames U and L may be provided with outstanding studs 250 upon which the supporting devices may be pivoted, and with lugs 251 for supporting the adjusting bolts 174 and the springs 173 thereof.

In my copending application, Ser. No. 76,911, filed Feb. 8, 1916, for an improvement in multiple loop cutter mining machines, I have claimed the multiple loop chain cutting mechanism herein disclosed as having unobstructed openings therethrough. Said copending application is directed both to the multiple loop chain cutting mechanism used separately and in combination with the horizontal kerf cutting mechanism hereinbefore described.

This application is a continuation in part of my co-pending application, Serial No. 775,173, filed June 28, 1913, apparatus for mining coal, and in the latter are presented broad claims to the common subject-matter, including mining apparatus comprising a wheel truck movable on a trackway with a chain-cutter mounted thereon in position to be presented to the coal face edgewise thereto and self-contained power-operated means for moving the chain-cutter bodily rectilinearly relatively to the trackway, about its pivot in the same plane and reversely rectilinearly to insert a horizontal parallel kerf in the coal face in front of the end of the trackway.

What I claim is:

1. The combination of a rotary supporting frame, means for rotating said frame, cutting mechanism mounted upon said frame and rotatable therewith in a given plane, and yielding means operating in the kerfs cut by said cutting mechanism to hold off the undercut material from the cutting mechanism.

2. The combination of a rotary cutting mechanism, and yielding means carried thereby and operating in the kerfs cut thereby to yieldingly support the undercut material.

3. The combination with a supporting frame, of a kerf cutter mounted thereon,

means for operating said kerf cutter, and a device mounted on said frame for movement relatively thereto independently of the movement of said kerf cutter, said device being movable bodily with said kerf cutter to support material above said kerf cutter to prevent such material from retarding the feeding movement of said kerf cutter.

4. The combination of cutting mechanism operable to cut kerfs in the material to be mined and embodying a flat elongated frame and a cutting chain traveling around the periphery thereof, and a yieldable supporting device mounted in said frame and adapted to yieldingly wedge in the kerf cut by the cutting mechanism and support the undercut material.

5. In a mining machine, the combination with a flat elongated frame having a chain-cutter traveling around the periphery thereof in the plane of said frame, of means for operating said chain-cutter including the feed of said frame in a transverse direction to cut a plane kerf, and an additional elongated frame immediately following said first-named frame in the kerf cut by said chain-cutter and in substantial parallelism with said first-named frame but separate therefrom for supporting the material above said kerf-cutter during the operation thereof to retard sagging tendency of said material to counteract settling of said cutter.

6. The combination of kerf cutting mechanism, and yielding means carried thereby and operable in the kerf cut thereby to prevent the undercut material from settling upon the cutting mechanism.

7. The combination of kerf cutting mechanism, and pivoted means trailing behind said cutting mechanism and the kerf cut thereby for supporting the undercut material.

8. The combination of kerf cutting mechanism, and a flat solid supporting member pivotally and yieldingly mounted to trail in the kerf behind the cutting mechanism and to prevent the material from dropping upon and binding said cutting mechanism.

9. In a mining machine, the combination of a flat elongated frame, of a traveling chain-cutter on the periphery of said frame, means extending at right angles to the plane of said frame and said chain-cutter within the periphery of the latter for operating the same, and mechanism for tilting said frame relatively to the axis of said operating means.

10. In a mining machine, the combination with a supporting frame, of horizontally movable kerf cutting mechanism mounted thereon, a flat elongated frame mounted on said supporting frame in fixed relation to said kerf cutting mechanism and in position to extend through the kerf cut by said horizontal kerf cutting mechanism, a vertical kerf cutting mechanism mounted at that end of said flat frame remote from said support-

- ing frame, said flat frame extending along said horizontal kerf cutting mechanism to support said vertical kerf cutting mechanism in close proximity to the outer end of said 5 horizontal kerf cutting mechanism, and means for operating said kerf cutting mechanisms including feeding movements thereof along a direction extending transversely of said horizontal kerf cutting mechanism and 10 transversely of said flat frame.
11. In a mining machine, the combination with a supporting frame, of a plurality of chain kerf cutters each comprising an endless cutter chain travelling about a cutter frame 15 in position to cut a plane kerf, means for carrying said kerf cutters one above the other on said frame to extend laterally therefrom, and means on said frame and extending to positions within the peripheries of said cutter chains to drive the latter, means for feeding the chain kerf cutters along a mine wall, and means for adjusting the inclination of 20 said kerf cutters relatively to each other and relatively to said frame.
12. In a mining machine, the combination with an elongated chain-cutter for cutting a kerf in a mine wall, means for operating said chain-cutter including feed transversely thereof, a second kerf-cutter for cutting an 25 intersecting kerf at or near the inner end of said first-named kerf, a flat elongated frame for carrying said second-kerf-cutter at one end thereof and mounted for movement transversely to the kerf produced by said 30 first-named kerf-cutter, and means extending through said flat elongated frame for transmitting power to said second-named kerf-cutter.
13. In a mining machine, the combination 35 with a supporting frame, of a kerf-cutter projecting laterally therefrom, of means for operating said kerf-cutter including feed transversely thereof, a rotary cutter for cutting an intersecting kerf, a supplemental 40 frame connected at one end to said supporting frame and carrying said rotary cutter at its outer free end, and means for transmitting driving power close to the periphery of said rotary cutter through said supplemental 45 frame while the latter moves transversely 50 through a kerf cut by said first-named kerf-cutter.
14. In a mining apparatus, the combination with a flat elongated chain-cutter, of 55 means for operating said chain-cutter including feed transversely thereof to cut a kerf in a mine wall, a supporting frame to which said chain-cutter is connected and from which said chain-cutter projects laterally, a 60 rotary kerf-cutter, an elongated frame connected at one end to said supporting frame and projecting laterally therefrom and carrying said rotary kerf-cutter at its outer free 65 end, and means for operating said rotary kerf-cutter including feed transversely of 70 said elongated frame through the kerf produced by said first-named kerf-cutter to cut an intersecting kerf immediately in the rear of said first-named kerf-cutter, said operating means comprising mechanism for transmitting power from the source of power on 75 said supporting frame through the kerf produced by said first-named kerf-cutter to substantially the periphery of said rotary cutter.
15. The combination of mechanism for cutting a horizontal kerf in the material to be mined, a rotary cutter operable immediately in the rear of said cutting mechanism for cutting a transverse intersecting kerf, a 80 movable support carrying said horizontal kerf cutting mechanism and said rotary transverse cutter, a source of power on said support, and a plurality of shafts arranged in the same plane and connected between said 85 source of power and said rotary cutter for distributing the transmission of power through the horizontal kerf to the rotary cutter.
16. The combination of means for cutting a kerf extending into the material to be 90 mined, a rotary cutter operable within the body of the material to be mined for cutting an intersecting kerf, a support movable in said first mentioned kerf for supporting said rotary cutter, and a plurality of parallel 95 shafts mounted in said support and connected with said rotary cutter near its periphery for transmitting power thereto.
17. The combination of means for cutting a kerf extending into the material to be 100 mined, a rotary cutter operable within the body of the material to be mined for cutting an intersecting kerf, a support movable in said first mentioned kerf for supporting said 105 rotary cutter, a plurality of parallel shafts mounted in said support and connected with said rotary cutter near its periphery for transmitting power thereto, and a central driving shaft mounted in said support and connected to said rotary cutter at its axis.
18. The combination of means for cutting a kerf extending into the material to be 110 mined, a rotary cutter operable within the body of the material to be mined for cutting an intersecting kerf, a support movable in said first mentioned kerf for supporting said 115 rotary cutter, a driving shaft mounted in said support and connected to said rotary cutter at its axis, and supplemental driving shafts mounted in said support and connected to said rotary cutter substantially at its periphery.
19. In a mining machine, the combination with kerf-cutting mechanism having a frame, and yielding means carried by said frame and engaging both walls of the kerf produced by said kerf-cutting mechanism substantially at right angles to said kerf.
20. In a mining machine, the combination of kerf-cutting mechanism, and yielding buf- 120 125 130

- fer means connected thereto and operating entirely within the kerfs in opposite directions and at substantially right angles to said kerfs and said cutting-mechanism.
- 5 21. In a mining machine, the combination of mechanism for cutting a substantially horizontal kerf in a mine wall, and yielding means operating entirely within said kerf to press upwardly against the body of material 10 above.
22. In a mining machine, the combination with a substantially horizontal flat frame, of vertical kerf cutting mechanism mounted at the outer end of said frame, and yielding 15 means carried by said frame and operating in a horizontal kerf to tend to spread apart the material bounding said horizontal kerf.
23. In a mining machine, the combination with kerf-cutting mechanism comprising a 20 frame and an endless chain cutter traveling around said frame, telescoping cups mounted on said frame within the boundary thereof, a spring tending to spread said cups apart to cause them to engage the walls of the kerf 25 produced by said kerf-cutting mechanism, and means for limiting the movement of said cups relatively to said frame.
24. In a mining machine, the combination with a traveling frame, of a chain kerf-cutter 30 mounted on said frame to travel about the same, telescoping cups mounted in said frame within the area surrounded by said chain kerf-cutter, guides on said frame for limiting the movement of one of said guides relatively to said frame, a spring inside of said 35 cups tending to spread them apart and press them against the walls of the kerf produced by said kerf-cutter, and means connected between said cups for limiting relative movement.
- 40 25. In a mining machine, the combination with a frame adapted to be moved along the kerf in a mine wall, of telescoping cups having annular flanges fitting in circular recesses 45 on opposite sides of said frame, a bolt fixed to one of said cups and extending into a hollow projection of the other cup, means for adjusting the initial relative positions of said cups, and a spring inside of said cups 50 surrounding said hollow projection and said bolt and tending to spread apart said cups to cause the same to engage the walls of said kerf spaced from the upper and lower surfaces of said frame.
- 55 26. In a mining machine, the combination with a supporting frame, a kerf cutting mechanism mounted thereon, means for operating said kerf cutting mechanism including the feed thereof, a device mounted on said 60 supporting frame in position to move bodily in approximately the same plane as said cutting mechanism, and pivoted to said supporting frame for movement relatively thereto and relatively to said kerf cutting mechanism 65 transversely of the plane of the latter, and means for causing said device to have a tendency to support material above the same during feeding movement of said kerf cutting mechanism.
- 70 27. In a mining machine, the combination with a supporting frame, of an elongated kerf cutter comprising an elongated cutter frame and an endless cutter chain travelling about the same, means for carrying said elongated kerf cutter on said supporting frame 75 in position to extend from said supporting frame deep into a mine wall, and elongated means connected at one end to said supporting frame and trailing transversely behind said kerf cutter in the kerf produced thereby in 80 position tending to support the material above said cutting mechanism to increase the freedom of feeding movement of said kerf cutter.
28. In a mining machine, the combination with a supporting frame, of kerf cutting 85 mechanism mounted thereon in position to project from said supporting frame into an upright mine wall, means independent of said kerf cutting mechanism but mounted on said supporting frame in position to project 90 therefrom into the kerf cut by said kerf cutting mechanism, means for operating said kerf cutting mechanism including the feed thereof, and means acting on said independent supporting member to move the same 95 relatively to said supporting frame against the body of material above the kerf to counteract the tendency of the cut material to sag and retard feeding movement of said kerf cutting mechanism.
- 100 29. In a mining machine, the combination with kerf-cutting mechanism, of a frame therefor, and an independent supporting member pivotally and yieldingly mounted to trail a predetermined distance behind said kerf-cutting mechanism in the kerf produced thereby.
- 105 30. In a mining machine, the combination with a supporting frame, of kerf cutting mechanism mounted thereon, a flat member 110 mounted on said supporting frame to have relative freedom of movement transversely of the kerf cut by said kerf cutting mechanism and in position to project into a line wall along the kerf produced by said kerf cutting mechanism while trailing behind the latter, and means acting on said flat plate to cause it to exert a yielding upward supporting force on the material above the kerf and back of the kerf cutting mechanism during the 115 feed of the latter.
31. In a mining machine, the combination with kerf-cutting mechanism, of a frame carrying the same, a flat supporting plate pivoted to said frame to permit said plate to 120 move transversely of the kerf produced by said kerf-cutting mechanism, said plate being movable bodily with said kerf-cutting mechanism in approximately the same plane, and mechanism counteracting the weight of the 125

free end of said plate for holding the latter in position to cause it to tend to support material above the same.

32. In a mining machine, the combination 5 with cutting mechanism, of a frame therefor, a plate pivoted to said frame and movable with the feeding movement of said cutting mechanism, a lever arm connected to said plate, and a spring acting on said lever arm 10 to hold said plate in a position tending to support material above the same.

33. In a mining machine, the combination 15 with cutting mechanism, of a frame, a flat supporting plate pivoted to said frame, a lever arm connected to said plate, a spring 20 acting on said lever arm tending to force said plate upwardly, and means coacting with said spring to adjust the position thereof and the initial position of said plate.

20 34. In a mining machine, the combination 25 with a flat frame adapted to move bodily transversely thereof along a kerf in a mine wall, of a kerf-cutter at one end of said flat frame in position to cut an intersecting kerf spaced back from the face of the mine wall, and internal peripheral driving mechanism 30 for said kerf-cutter.

35. In a mining machine, the combination 30 with an upright rotary kerf-cutter, of a flat frame carrying said kerf-cutter at one end thereof in a plane substantially at right angles to the plane of said flat frame, and peripheral driving mechanism carried by 35 said frame and connected to said cutter to operate the latter to cut a kerf spaced back from the face of the mine wall and intersecting the kerf along which said flat frame is movable.

40 36. In a mining machine, the combination 45 with a frame movable along a kerf extending into a mine wall from the face thereof, of a rotary disc-cutter carried by that portion of said frame which projects into such kerf, a driving shaft mounted in said frame, gearing carried partly by said kerf-cutter within the 50 plane of the latter and partly by said shaft, means for rotating said shaft to cause said gearing to rotate said kerf-cutter, and means for feeding said kerf-cutter during the rotation thereof to cut a kerf spaced back from the mine wall in a plane intersecting the 55 plane of said first-named kerf.

37. In a mining machine, the combination 60 with a disc kerf-cutter, of a gear connected thereto in the plane thereof to move therewith, a flat frame for carrying said kerf-cutter in a plane substantially at right angles to said flat frame, and means connected to 65 said flat frame at the end thereof opposite said kerf-cutter and extending through said frame to said kerf-cutter for operating the latter.

38. In a mining machine, the combination 70 with a rotary kerf-cutter, of an annular gear mounted on said kerf-cutter and rotating

therewith, a pinion meshing with said gear, a frame for supporting said kerf-cutter in a plane at substantially right angles thereto, said frame being movable along a kerf extending into a mine wall from the face thereof, a shaft mounted in said frame and connected to said pinion at right angles to the plane of said kerf-cutter, means for driving said shaft from the end of said frame opposite said kerf-cutter to effect the rotation 75 of the latter through said gearing, and means for feeding said kerf-cutter during the rotation thereof by moving said frame transversely thereof along said kerf to produce an additional kerf spaced back from the mine 80 wall and intersecting the plane of said first-named kerf.

39. In a mining machine, the combination 85 with a rotary kerf cutter, of a gear mounted thereon to rotate therewith, a frame for carrying said kerf cutter, a plurality of pinions meshing with said gear on opposite sides of the center thereof, a plurality of driving shafts mounted on said frame and connected respectively to said pinions, and means for 90 rotating said shafts to effect the rotation of said kerf cutter.

40. In a mining machine, the combination 95 with a frame, of a rotary kerf cutter pivoted to said frame, a gear mounted on said kerf cutter and rotating therewith, a plurality of diametrically disposed pinions meshing with said gear, a plurality of driving shafts connected respectively to said pinions, and means for simultaneously rotating said driving 100 shafts to effect the rotation of said kerf cutter.

41. In a mining machine, the combination 105 with a flat frame adapted to move through a kerf in a mine wall, of a rotary kerf cutter pivoted to one end of said frame, a gear carried by said kerf cutter and rotating therewith, a plurality of pinions meshing with said gear, a plurality of drive shafts mounted in said frame and connected respectively to said pinions, an annular driving gear mounted 110 near the other end of said frame, additional pinions meshing with said annular gear and connected respectively to the other end of said drive shafts, and means for rotating said annular gear to effect rotation of said kerf cutter. 115

42. In a mining machine, the combination 120 with a frame, of a central longitudinal drive shaft mounted on said frame, a rotary kerf cutter mounted on said shaft to be driven thereby, a gear mounted on said kerf cutter and movable therewith, a pinion meshing with said gear, an additional drive shaft mounted in said frame and connected to said pinion, and means for rotating said shafts at different rates of speed to effect the transmission of rotary power to said kerf cutter from both of said drive shafts.

43. In a mining machine, the combination 125 with a plurality of kerf cutters spaced apart,

of means for operating said kerf cutters, and a plurality of supporting devices, one less in number than the number of said kerf cutters and each yieldingly mounted for entering the kerfs and assisting in supporting material above the same.

44. In a mining machine, the combination with a plurality of kerf cutters for producing parallel spaced apart kerfs in a mine wall, 10 of means for operating said kerf cutters, and pivoted yielding devices associated with the kerf cutters below the uppermost kerf cutter for entering the corresponding kerfs respectively and assisting in supporting the material above the same.

45. In a mining machine, the combination with a plurality of substantially horizontal kerf cutters for producing parallel kerfs spaced apart in a mine wall, of an additional 20 kerf cutter for producing a vertical kerf at the inner end of an intermediate kerf, and pivoted plates one associated with the vertical kerf cutter and the other associated with the horizontal kerf cutter below 25 the same, to assist in supporting the material above the said plates while said vertical kerf cutter is operating.

46. In a mining machine, the combination with a vertical kerf cutter, of a frame carrying 30 the same and adapted to move through a horizontal kerf in a mine wall, means for operating said kerf cutter, means for feeding said frame and said kerf cutter during the latter's operation, and automatic mechanism 35 for oscillating said frame longitudinally during its feeding motion to effect the lateral oscillation of said kerf cutter during the latter's operation.

47. In a mining machine, the combination 40 with kerf-cutting mechanism, of means for operating the same, automatic mechanism for reciprocating said kerf-cutting mechanism transversely to the plane thereof, and means for positively holding said kerf-cutting mechanism against reciprocation during operation 45 of said cutting mechanism.

48. In a mining machine, the combination with cutting mechanism, of a frame for carrying the same, means for operating said cutting mechanism including the feed thereof, 50 an additional frame for supporting said first-named frame for reciprocating movement relatively to said additional frame, and cam apparatus for reciprocating said first-named 55 frame and said cutting mechanism transversely of the direction of feed thereof said cam apparatus being in continuous connection with said first-named frame to at all times positively move said first-named frame 60 in one direction or the other, and hold said frames in predetermined relation.

49. In a mining machine, the combination with a vertical rotary kerf-cutter, of an elongated frame extending into the kerf from the 65 face of a mine wall and movable transversely

along said kerf and carrying said kerf-cutter at the outer end thereof, means for operating said kerf-cutter including the feed of said frame along said kerf transversely of said frame to cut a vertical kerf intersecting the 70 plane of said first-named kerf, and automatic mechanism for reciprocating said kerf-cutter transversely of itself during the aforesaid operation thereof.

50. In a mining machine, the combination 75 with a supporting frame, of a supplemental frame mounted thereon for reciprocatory movement relatively thereto, cutting mechanism mounted on said supplemental frame, means for operating said cutting mechanism 80 including the feed thereof, apparatus for compelling positive movement of said supplemental frame in both directions to secure reciprocation of said cutting mechanism relatively thereto, and means for rendering 85 said reciprocating apparatus inoperative and holding said supplemental frame against reciprocation relatively to said supporting frame.

51. In a mining machine, the combination 90 with cutting mechanism, of means for operating the same, a frame for carrying said cutting mechanism, a cam, a device connected to said frame for engaging said cam, a relatively movable device mounted on said frame and 95 also engaging said cam, means for holding said relatively movable device in operative position relative to said cam, and apparatus for operating said cam to effect the longitudinal oscillation of said frame and lateral oscillation of said cutting mechanism.

52. In a mining machine, the combination with cutting mechanism, of a frame carrying the same, a cam, a member extending from said frame to engage said cam, a plate slideable on said frame, a member extending from said plate for engaging the opposite side of said cam, a pin extending through said plate into an opening in said frame to hold said engaging members in operative position, said 100 pin extending into another hole in said frame for holding said members in inoperative position, and means for operating said cam to effect oscillation of said frame and said cutting mechanism when both of said members 110 engage said cam.

53. In a mining machine, the combination with cutting mechanism, of a frame, means for operating said cutting mechanism, an engaging member extending from said frame, a 120 plate slidably mounted on said frame and having two engaging members on opposite sides to said first named engaging member, a cam operable between the engaging member of said frame and one of the engaging members of said plate, a rotary collar between the engaging member of said frame and the other engaging member of said plate, locking mechanism for holding the engaging members of said plate in predetermined positions 125 relative to the cam.

54. In a mining machine, the combination with a vertical rotary kerf cutter, of a flat elongated frame for carrying said kerf cutter, a bracket for slidably supporting said frame, a plate slidable on said frame, means for locking said plate in two predetermined positions, two members on said plate, a collar engaging one of said members, a cam engaging the other member, an additional engaging member on said frame and located between said collar and said cam, and means for rotating said cam.
55. In a mining machine, the combination with cutting mechanism, of a support, a frame carrying said cutting mechanism and slidably mounted on said support, a plate slidably mounted on said frame, a stop, an engaging member on said frame on one side of said stop, an engaging member on said plate on the other side of said stop, means for locking said plate in a predetermined position with said engaging members on opposite sides of said stop to prevent longitudinal movement of said frame, a cam, an additional engaging member engaging one side of said cam and mounted on said plate, means for locking said plate in the position where the additional engaging member of said plate is on one side of said cam, and the engaging member on said frame is on the other side thereof, and means for rotating said cam to effect the oscillation of said frame and cutting mechanism.
56. In a mining machine, the combination with kerf-cutting mechanism, of a frame for carrying the same at the outer end thereof in a plane at right angles to the longitudinal axis of said frame, peripheral driving means for said kerf-cutting mechanism extending along said frame substantially perpendicular to the plane of said kerf-cutting mechanism, and means for oscillating said kerf-cutting mechanism during operation without interfering with the operation of said peripheral driving means.
57. In a mining machine, the combination with a supporting frame, of a supplemental frame having a vertical extension connected to said supporting frame and having also a horizontal extension, an auxiliary frame pivotally connected on a horizontal axis to said horizontal extension, an individual kerf cutter mounted on said auxiliary frame in position to cut a plane kerf in a mine wall, means for operating said kerf cutter including feed thereof along the plane of said kerf cutter to gradually increase the depth of the kerf cut by said kerf cutter a substantial distance into the mine wall, mechanism between said supporting frame and the vertical extension of said supplemental frame for adjusting the position of said kerf cutter in varying planes parallel to each other and holding the same in adjusted position, and means for moving said auxiliary frame relatively to said supplemental frame on said horizontal axis to adjust the position of said kerf cutter relatively to said supporting frame.
58. In a mining machine, the combination with a plurality of spaced-apart individual kerf-cutters adapted to cut spaced-apart kerfs in a wall of coal, of a supporting frame therefor, means for operating said kerf-cutters to produce separate plane kerfs in an upright mine wall of coal adjacent said frame, and apparatus for simultaneously adjusting the cutting positions of said kerf-cutters toward and from each other and holding them in adjusted position.
59. In a mining machine, the combination with a plurality of spaced-apart individual kerf-cutters, of a main frame for supporting said kerf-cutters for operation in an upright mine wall of coal adjacent said frame, a plurality of supplemental frames for carrying said kerf-cutters respectively, means for operating said kerf-cutters to produce separated spaced-apart kerfs in an upright wall of coal adjacent said frame, and apparatus for simultaneously moving both of said supplemental frames toward each other and away from each other to adjust the distance between said kerf-cutters when in cutting positions.
60. In a mining machine, the combination with a plurality of cutting mechanisms for producing spaced-apart kerfs in a wall of coal, of a main frame for supporting said kerf-cutting mechanisms in position for cutting kerfs in an upright coal wall adjacent said frame, supplemental frames movably mounted on said main frame and supporting respectively said cutting mechanisms, and a counterbalancing connection between said supplemental frames.
61. In a mining machine, the combination with an upper kerf cutter and a lower kerf cutter, of means for simultaneously operating said kerf cutters, a main frame, supplemental frames connected respectively to said upper and lower kerf cutters, and gearing for lifting one of said supplemental frames while lowering the other, and while said kerf cutters together with said supplemental frames respectively balance each other.
62. In a mining machine, the combination with a main frame, of supplemental frames movably mounted on said main frame, cutting mechanisms respectively mounted on said supplemental frames in position for producing spaced-apart kerfs in a mine wall, and connections between said supplemental frames for counterbalancing the weight of each supplemental frame and the cutting mechanism carried thereby against the weight of the other supplemental frame and the cutting mechanism carried thereby.

63. In a mining machine, the combination with a kerf cutter, of means for operating the same, a main frame, a supplemental frame movable vertically in said main frame and carrying said kerf cutter, means for counterbalancing said supplemental frame and kerf cutter in its vertical adjustments, and manually operated gearing for moving said supplemental frame to adjust the elevation of 10 said kerf cutter.

64. In a mining machine, the combination with an upper kerf cutter and a lower kerf cutter, of means for operating said kerf cutters, a main frame, supplemental frames slidably mounted on said main frame and respectively supporting said kerf cutters, rack gearing on said supplemental frames, and a single pinion mounted on said main frame and engaging the rack gearing on both of said 15 supplemental frames to effect the lifting of one of said kerf cutters while lowering the other, and while the weight of one kerf cutter and its supplemental frame is counterbalanced by the weight of the other kerf cutter 20 and its supplemental frame.

65. In a mining machine, the combination with a plurality of kerf cutters spaced apart, of means for operating said kerf cutters, a main frame, supplemental frames respectively carrying said kerf cutters, bifurcated extensions on said supplemental frames sliding in said main frame past each other in opposite directions, racks on said bifurcated extensions, a pinion engaging the respective 30 racks of said bifurcated extensions, and means for rotating said pinion to secure movement of said extensions in opposite directions and movement of said kerf cutters away from or toward each other while said 35 kerf cutters and the respective supplemental frames are balanced against each other.

66. In a mining machine, the combination with a kerf cutter comprising a cutter chain and a cutter frame, of a support for said cutter frame, means for driving said cutter chain, and a detachable connection between said cutter frame and said support, said detachable connection comprising mechanism for tightening the connection when said kerf cutter is 45 cutting a kerf in a body of material and for permitting detachment of said kerf cutter from said support when moved in the opposite direction relatively to said support.

67. In a mining machine, the combination with a flat chain-cutter, of a frame therefor, means for driving said chain-cutter, a support for said frame, and a bayonet joint detachably connecting said frame to said support permitting detachment of said chain-cutter when 55 moved in the direction of feed relatively to said support.

68. In a mining machine, the combination with a kerf-cutter, of a frame therefor, a support for said frame, means for operating such 65 kerf-cutter including the feed thereof, and a

bayonet joint between said kerf-cutter frame and said support to permit detachment of said frame and kerf-cutter from said support when said frame is moved in feeding direction relatively to said support, said bayonet joint comprising cam surfaces for effecting firm locking of said joint when said cutter is operated including feeding thereof. 70

69. In a mining machine, the combination with a supporting frame, of a plurality of individual kerf cutters mounted on said frame, means for operating said kerf cutters, and manually operated mechanism for simultaneously moving said kerf cutters relatively to said supporting frame while maintaining 80 them in parallelism to adjust the distance between said kerf cutters. 75

70. In a mining machine, the combination with a supporting frame, of a plurality of kerf-cutters mounted on said supporting frame, and manually operated means for simultaneously adjusting the uppermost and lowermost kerf-cutters toward and from each other relatively to said supporting frame while maintaining such uppermost and lowermost kerf-cutters, in parallelism. 90

71. In a mining machine, the combination with a main frame, of a right angle supplemental frame having its vertical portion slidably guided along guideways on said main frame and confined to upright rectilinear movements, a kerf-cutter mounted on the horizontal portion of said right angle supplemental frame, means for operating said kerf-cutter, and mechanism comprising gear 100 teeth on the vertical portion of said right angle supplemental frame for adjusting the position of the latter to vary the position of said kerf-cutter to planes parallel to each other. 105

72. In a mining machine, the combination with a supporting frame, of an individual roof kerf cutter comprising a cutter-chain mounted on said supporting frame and confined to feeding movements in horizontal 110 planes, an individual floor kerf cutter comprising a cutter chain mounted on said frame and confined to feeding movements in horizontal planes parallel to the planes of feeding movement of said roof kerf cutter, means for operating said kerf cutters including feeding movements thereof in such parallel planes, and means for adjusting the distance between the cutting positions of said kerf cutters while maintaining them in parallelism, in accordance with the position of the floor and roof of the mine chamber adjacent said supporting frame. 115

73. In a mining machine, the combination with a supporting frame, of a plurality of spaced-apart chain kerf-cutters mounted on said frame for cutting spaced-apart kerfs in a mine wall adjacent said frame, and mechanism comprising flexible driving connections extending transversely to the planes of such 125 130

kerf-cutters and between the same for operating the latter.

74. In a mining machine, the combination with a supporting frame, of chain kerf-cutting mechanism mounted on said frame for cutting a plane kerf in a mine wall adjacent said frame, and means comprising a flexible driving connection at said kerf-cutting mechanism mounted on said frame for operating 10 said chain kerf-cutter in various adjusted planes relatively to said driving connection.

75. In a mining machine, the combination with a supporting frame, of spaced apart chain kerf cutters mounted on said frame for 15 cutting spaced apart kerfs in a mine wall adjacent said frame, means common to both of said chain kerf cutters to operate the same, including simultaneous feed thereof to cut such spaced apart kerfs, means for adjusting the 20 inclinations of said chain kerf cutters relative to said supporting frame, and means for adjusting the distance between said chain kerf cutters.

76. In a mining machine, the combination 25 with a supporting frame, of driving mechanism comprising a rotary gear mounted on a fixed pivotal axis relatively to said frame and having a hollow slotted hub, a chain kerf-cutter mounted on said frame for cutting a kerf in a plane transverse to the axis of rotation of said rotary gear, and a flexible driving connection between said slotted hub and said chain kerf-cutter.

77. In a mining machine, the combination 35 with a supporting frame, of a rotary gear pivotally mounted on said frame, a chain kerf cutter mounted on said frame in position to cut a kerf in a plane substantially at right angles to the axis of rotation of said gear, 40 and a driving shaft flexibly connected to the hub of said rotary gear at one end of said shaft and flexibly connected to said kerf cutter at the other end of said shaft, said shaft being located along a line extending transversely of said chain cutter within the peripheral path of travel of the chain thereof.

78. In a mining machine, the combination with a supporting frame mounted on wheels, of a supplemental frame mounted for up and 50 down movement on such main frame, an auxiliary frame pivotally connected to said supplemental frame on a horizontal axis substantially parallel to a mine wall, chain kerf-cutting mechanism mounted on such auxiliary frame, means for adjusting the inclination of said cutting mechanism by moving said auxiliary frame on said horizontal axis relatively to said supplemental frame, means for rectilinearly adjusting the elevation of 55 said supplemental frame relatively to said main frame to adjust the elevation of said kerf-cutting mechanism by rectilinear movement transversely thereof, and means for driving said kerf-cutting mechanism at its

adjusted inclination and adjusted elevation, 65 and propelling mechanism for driving said wheels to feed said kerf-cutting mechanism to cut a kerf in an upright mine wall adjacent said supporting frame.

79. In a mining machine, the combination 70 with a supporting frame, of a chain kerf cutter comprising an endless cutter chain and a flat cutter frame, means for adjusting the inclination of said kerf cutter relative to said supporting frame, and means for operating 75 said chain kerf cutter, comprising a driving shaft flexibly connected to said cutter chain to permit such adjustment, and located on a line extending transversely of said chain kerf cutter within the boundary of the path of 80 travel of said chain.

80. In a mining machine, the combination with a main frame comprising an upright guideway, of a supplemental frame having 85 a vertical bifurcated extension slidable vertically along said guideway, a horizontal angular extension from said supplemental frame, a kerf cutting mechanism mounted on said angular extensions and confined to positions approximately in a horizontal plane, 90 means for operating said kerf cutting mechanism, and mechanism comprising a rack in the said bifurcated extension and a pinion in said guideway meshing with said rack for rectilinearly adjusting the position of said 95 kerf cutting mechanism in different planes parallel to each other.

81. In a mining machine, the combination with supporting framework, of a chain kerf cutter for cutting a plane kerf and comprising 100 a cutter chain and a cutter-frame, means for pivotally supporting said cutter-frame on said supporting framework for movement relatively thereto on a horizontal axis, worm gear mechanism interposed between 105 said supporting framework and said means for thus supporting said cutter-frame, for varying the inclination of said plane kerf cutter transversely of its plane, and means on the supporting framework and supported 110 separately from the said cutter so as not to partake of the adjusting movements of the latter, said means comprising a driving member located along a line extending transversely of the plane of said kerf cutter within the 115 closed path of travel of said cutter chain for driving the latter.

82. In a mining machine, the combination with a supporting frame, of a roof chain kerf-cutter, a floor chain kerf-cutter, auxiliary frames for supporting said kerf-cutters on said supporting frame for movement relatively to said supporting frame, means individual to each of said kerf-cutters and to each 120 of said auxiliary frames for varying the inclination of said kerf-cutters transversely of their planes respectively, and manually operated means for actuating said auxiliary

frames to move them respectively relatively to said supporting frame to adjust the distance between said kerf-cutters.

83. In a mining machine, the combination with a plurality of spaced apart kerf cutter chains, of a supporting frame, driving mechanism comprising a rotary grooved hub pivoted to said frame, a sprocket mounted directly on said hub to drive one of said kerf cutter chains, and flexible connections comprising shafts with heads engaging the grooved hub for driving the other kerf cutter chains.

84. A mining machine comprising a supporting frame, kerf cutting mechanism mounted on said frame and comprising a rotary hollow slotted hub, power operated mechanism comprising a cylindrical hub pivotally mounted on said supporting frame and having a longitudinally slotted interior, a shaft having heads at its ends engaging said hubs and slidable along said cylindrical pivoted hub within the same, means for effecting feeding movement of said kerf cutting mechanism, and a motor for driving said feeding means and said power operated mechanism to secure operation of said kerf cutting mechanism including the drive thereof through said flexible connections comprising said slotted hubs and said shaft.

85. In a mining machine, the combination with a supporting frame, of a chain kerf cutter mounted on said frame for operation in approximately horizontal planes, means for adjusting the elevation of said kerf cutter relatively to said supporting frame by movement of said kerf cutter transversely of its plane and while said kerf cutter remains on a predetermined side of said supporting frame, and means comprising a single rigid shaft with flexible connections at its ends to serve as a laterally extensible driving connection substantially at right angles to the plane of said kerf cutter in the various adjusted positions of the latter, for operating said chain kerf cutter.

86. In a mining machine, the combination with a supporting frame, of a gear mounted on said frame for tilting movement relatively thereto and having a hollow slotted hub, a chain kerf cutter supported by said frame and comprising a sprocket wheel mounted to rotate with said hub, an additional chain kerf cutter mounted on said frame comprising an additional hollow slotted hub, and a shaft having heads engaging the slots in said hubs to form a rolling mill joint between the aforesaid gear and said additional chain kerf cutter.

87. In a mining machine, the combination with a primary support, of a secondary support pivoted thereto, adjustable kerf-cutting mechanism mounted on said secondary support in position to produce a plurality of parallel spaced-apart individual kerfs in a

mine wall, means comprising flexible connections between said kerf-cutters for operating the same in their various adjusted positions, and mechanism for rotating the secondary frame together with said chain kerf-cutting mechanism to secure feeding movement of the latter in an arc relatively to said primary frame to cut the kerfs in a general horizontal direction across the mine wall adjacent the machine.

88. In a mining machine, the combination with spaced apart kerf cutters, of a main frame, two supplemental frames one for each of said kerf cutters, a rack on each of said supplemental frames, a pinion on the said main frame for simultaneously engaging both the racks on said supplemental frames, and means for operating said kerf cutters.

89. In a mining machine, the combination with spaced-apart kerf-cutters, of means for simultaneously operating said kerf-cutters, a main frame, supplemental frames connected respectively to said spaced-apart kerf-cutters, and means for moving said supplemental frames in opposite directions to adjust the distance between said kerf-cutters while said kerf-cutters together with said supplemental frames respectively balance each other.

90. In a mining machine, the combination with a wheel-supported rigid base frame simultaneously operating said kerf-cutters, of a mine track extending toward an upright mine wall, of a supplemental supporting frame mounted on said base frame for pivotal movement relatively thereto on an upright axis extending through both frames, a chain kerf cutter carried by said supplemental frame in position to initially extend laterally from said track along the floor of a mine chamber, means for adjusting the elevation of said kerf cutter while extending from the same side of said track and to cause said cutter to occupy positions for cutting a kerf approximately in the plane of the floor on which said track is laid, means for driving said kerf cutter at its adjusted elevation, and self-acting power mechanism for swinging said supplemental supporting frame about said upright axis on said base frame to secure arcuate feeding movement of said cutter to cut a kerf approximately in the plane of the floor on which the track is laid and from one side of said track to the other side thereof including a kerf in advance of the end of said track adjacent the upright mine wall.

91. In a track mounted mining apparatus adapted to cut a horizontal kerf extending across its front from one side of the track to the other, the combination with a rigid base frame, of supporting wheels therefor resting upon and braced by the track, a laterally movable rigid cutter arm carried by the base frame and extending therefrom in elevated normally horizontal planes above the other parts of the apparatus, an endless cutter chain mov-

able along the cutter arm in a path normally horizontal throughout, mechanism below the plane of said arm but adjacent thereto for adjusting the arm angularly transversely of its own plane, means for adjusting the cutter arm vertically to move the cutter chain from one set of relatively elevated cutting planes to another set of more elevated cutting planes, a chain driving motor positioned below the plane of the cutter arm and mounted on said rigid base frame to move bodily therewith and bodily with said cutter arm in feeding direction but not carried by said cutter arm nor movable bodily therewith during such transverse angular adjustment thereof, and power actuated means below the plane of said arm for causing the latter and said chain to move laterally to cut a horizontal or an inclined kerf at any of several relatively high elevations and extending transversely from one side of the track to the other.

92. In track mounted mining apparatus adapted to cut a horizontal kerf extending across its front from one side of the track to the other, the combination with a rigid base frame, of supporting wheels therefor resting upon and braced by the track, a laterally movable cutter arm carried by the base frame and extending horizontally therefrom, an endless chain cutter movable along the cutter arm in a horizontal path, a motor mounted on the said rigid base frame to move bodily therewith, means for bodily adjusting said arm vertically in parallelism independently of said motor to move the chain cutter from one set of relatively low cutting planes to another set of relatively high cutting planes, means for varying the inclination of said arm relatively to said base frame transversely of the plane of said arm and independently of said motor, driving connections between said motor and said endless chain cutter for driving the latter in its various adjusted positions, and power actuated means constructed and arranged to cause said arm and said chain cutter to move laterally to cut a horizontal kerf at any one of the several elevations and extending transversely from one side to the other of the track.

93. In a system of coal mining devices of the class described, the combination with a wheeled-truck adapted to run upon and be laterally braced by a track extending longitudinally toward a vertical coal face, of cutter mechanism supported upon said truck and movable horizontally along the plane of the floor on which said track is laid, while cutting across the front end of the track, a motor movable bodily with the cutter mechanism, propelling mechanism between said motor and the truck wheels, localized mechanism for vertically adjusting the motor and the cutting mechanism in horizontal parallelism and adapted to hold it either where it will form a kerf in relatively low horizontal planes at the

floor or where it will form a kerf in other horizontal planes relatively higher than those aforesaid, and power actuated mechanism for causing the said transverse movement of the cutter mechanism across the front end 70 of the track while in operation.

94. In a coal cutting machine, the combination with a base, of framework rotatably mounted on said base but confined against up or down tilting movements relatively to said base, elongated chain kerf cutting mechanism extending horizontally from said framework, means mounted on said framework for driving said elongated chain kerf cutting mechanism, means independent of said driving means for tilting said kerf cutting mechanism longitudinally up and down relatively to said frame work while the driving connections between said driving means and said elongated chain kerf-cutting mechanism are maintained, 80 and power operated mechanism for rotating said framework relatively to said base frame to feed said elongated chain kerf-cutting mechanism arcuately in its adjusted position, said framework and said driving means 90 mounted thereon being at all times confined against up or down tilting movements relatively to said base.

95. In a wheel-supported coal mining machine adapted to be transported over mine tracks and to cut a horizontal floor kerf while supported on a track extending longitudinally toward the face of the coal, the combination with a base frame, of track wheels supporting said base frame, cutter apparatus supported by and projecting horizontally from said base frame in position to cut a kerf in the plane of the floor on which the track is laid, said cutter apparatus being movable laterally in relation to the base frame while supported thereby to cut such a floor kerf extending transversely across the track on which the machine stands, said cutter apparatus comprising framework rotatably mounted on said base frame, mechanism for confining said framework against tilting movement up or down relatively to said base frame, mechanism mounted on said framework for driving said cutter apparatus and for moving said apparatus laterally in relation to said base frame, and means on said base frame for driving the track wheels to transport the machine from one working place to another, said driving apparatus comprising an electric motor mounted on said framework and rotatable therewith relatively to said base frame. 115

96. In a mining machine, the combination with a supporting frame, of a plurality of spaced apart kerf cutters comprising an upper kerf cutter, a lower kerf cutter and an intermediate kerf cutter, means for carrying said kerf cutters on said supporting frame in spaced apart relation and in position to cut a plurality of spaced apart horizontal 125

130

- kerfs in an upright mine wall, an auxiliary frame extending from said supporting frame along the kerf produced by said intermediate kerf cutter, an additional kerf cutter mounted 5 at the outer end of said auxiliary frame for driving movement relatively thereto to cut a kerf intersecting said intermediate kerf and extending toward the upper and lower kerfs produced by said upper and 10 lower kerf cutters, means for operating said kerf cutters including the feed thereof to cut horizontal spaced apart kerfs and the upper right intersecting kerf, and yielding means mounted on said supporting frame individual 15 to each of the horizontal kerf cutters below the uppermost in position to extend along the horizontal kerfs below the uppermost kerf and press against the respective bodies of material to counteract the 20 tendency thereof to sag and retard feeding movement of the kerf cutters below the uppermost kerf cutter.
97. In a mining machine, the combination with a truck adapted to run on a track in a 25 mine, of a supporting frame mounted for vertical adjustment on said truck and for rotation relatively thereto on an upright axis within the boundary of said truck, a kerf-cutter mounted on said supporting frame for 30 cutting a flat kerf in a mine wall in a single plane, self-acting power mechanism for operating said kerf-cutter including arcuate feed thereof by rotating said supporting frame relatively to said truck, means for adjusting 35 the inclination of said kerf-cutter relatively to said supporting frame while the latter remains in fixed relation to said truck, and separate and independent mechanism for adjusting the elevation of said kerf-cutter. 40
98. In a mining machine, the combination with a truck adapted to run on a mine track, of a supporting frame mounted on said truck for vertical adjustment relatively thereto, means for confining said supporting frame 45 against tilting movements relatively to said truck, means for adjusting the elevation of said supporting frame rectilinearly relatively to said truck, kerf cutting mechanism mounted on said supporting frame for cutting a flat kerf in a mine wall in a single 50 plane, said kerf cutting mechanism being permanently confined against lateral swinging movement relatively to said supporting frame, means for adjusting the inclination of 55 said kerf cutting mechanism relatively to said supporting frame by movement transversely of the plane of said kerf cutting mechanism, means comprising a flexible driving connection extending from said supporting frame to said kerf cutting mechanism, said flexible connection accommodating itself to the adjustments of inclination of said kerf cutting mechanism for operating the latter. 60
99. In a mining machine, the combination with a wheel-supported portable main frame, of a supplemental frame mounted on said main frame for vertical adjustment relatively thereto, a chain kerf cutter mounted on said supplemental frame, means for adjusting the elevation of said supplemental frame to effect adjustment of the elevation of said chain kerf cutter, a motor, guiding mechanism connected between said motor and said chain kerf cutter, and worm gear mechanism for varying the inclination of said chain cutter by moving the same on a horizontal transverse axis independently of any bodily movement of said motor, such variation of inclination of said chain cutter relatively to said supplemental frame being transversely of its own plane on an axis extending transversely relative to said chain cutter. 65
100. In a track-mounted mining apparatus adapted to cut a horizontal kerf extending across its front from one side of the track to the other, the combination with a rigid base frame, of supporting wheels therefor resting upon and braced by the track, a supplemental frame mounted on said base frame for vertical adjustment relatively thereto, mechanism for permanently confining said supplemental frame against tilting movement up or down relatively to said base frame, a narrow elongated cutter arm rigidly connected to said supplemental frame and extending horizontally therefrom, an endless chain cutter movable along said cutter arm in a path horizontal throughout, means for adjusting the arm angularly up and down relatively to said supplemental frame to adjust the cutting plane, means for adjusting the elevation of said supplemental frame relatively to said base frame to move the chain cutter from one set of relatively low-cutting planes to another set of relatively high cutting planes, a chain driving motor fixedly connected to said supplemental frame to move bodily therewith and bodily with said cutter arm, motor actuated means for transmitting power to said chain cutter, and means operated by said motor for rotating said supplemental frame relatively to said base frame to feed the chain cutter in an arc at any of its adjusted positions. 105
101. In a mining machine, the combination with a truck adapted to travel on a mine track, of a supporting frame on said truck, spaced apart plane kerf cutters on said supporting frame in position to project laterally therefrom to cut spaced apart kerfs along a mine wall parallel to said track, means individual to said kerf cutters to adjust the inclinations thereof on axes parallel to said track, and means for propelling said truck along said track to secure rectilinear feed of said kerf cutters transversely of the latter in their adjusted positions to cut spaced apart kerfs along parallel lines. 110
102. In a mining machine, the combination 115

with supporting framework, of spaced apart plane kerf cutters projecting laterally from said framework in position to cut spaced apart kerfs in a mine wall along horizontal 5 parallel lines, means for adjusting the elevation and inclination of said kerf cutters, and means operating said kerf cutters including rectilinear feed thereof transversely of themselves while projecting laterally from said 10 framework to cause said kerf cutters to cut kerfs along parallel and horizontal lines.

103. In a mining machine, the combination with a truck having wheels adapted to run on a mine track, of a supporting frame mounted 15 on said truck to rotate relatively thereto on an upright axis, means for holding said support against rotary movement relatively to said truck, horizontal kerf cutting mechanism mounted on said supporting frame and 20 extending therefrom in position to cut at the floor level a horizontal kerf in an upright mine wall, means mounted on said supporting frame and connected to said wheels for propelling the said truck while said supporting frame is confined against rotary movement 25 relatively to said truck, to effect rectilinear feeding movement of said kerf cutting mechanism to cut at the floor level, means for holding said truck against rectilinear movement, 30 and means for swinging said supporting frame when free to do so to effect arcuate feeding movement of said kerf cutting mechanism to cut at the floor level while said truck is held against movement along said track.

104. In a mining machine, a support, an overlying platform pivotally connected thereto, cutting mechanism carried on said platform including a cutter bar, power operated means for propelling said support, and 40 means operatively connected to said last-mentioned means for varying the position of said platform.

105. In mining apparatus, the combination with a truck movable on a trackway, of cutter mechanism pivotally mounted on said truck and comprising a cutter bar having a chain adapted to cut a kerf for said bar in a face when said bar is presented edgewise thereto, and self-contained power operated 45 means for moving the truck along said trackway to effect movement of said bar bodily rectilinearly of the trackway, about its pivot in the same plane, and reversely rectilinearly of the trackway to insert a parallel ribbed 50 kerf in a face in front of the end of the trackway.

106. In mining apparatus, the combination with a truck movable on a trackway, of cutter mechanism pivotally mounted on said truck and comprising a cutter bar having a chain adapted to cut a kerf for said bar in a face when said bar is presented edgewise thereto, and self-contained power operated 60 means for moving the truck along the trackway to move said bar about its pivot in the

same plane while said truck is stationary, and for reversing the movement of the truck along the trackway to move said bar reversely rectilinearly to insert a horizontal parallel ribbed kerf in a face in front of the end 70 of the trackway.

107. In mining apparatus, the combination with a wheeled truck movable on a trackway, of propelling mechanism therefor, cutter mechanism pivotally mounted 75 on said truck and comprising a cutter bar, and means co-acting with said truck propelling mechanism for moving said cutter bar angularly across the end of said truck in opposite directions while said truck remains stationary on said trackway.

108. In mining apparatus, the combination with a wheeled truck movable on a trackway, of cutter mechanism pivotally mounted thereon and comprising a cutter chain-carrying cutter bar, and self-contained power operated mechanism supported by said truck for moving said bar either angularly across the end of said truck while the latter is stationary or longitudinally relative to said 85 trackway at a feeding speed to cut either a right angle or a parallel face by moving the truck along the trackway.

109. In mining apparatus, the combination with a wheeled truck movable on a trackway, of cutter mechanism pivotally mounted thereon and comprising a cutter chain-carrying cutter bar adapted to swing across the end of the truck, mechanism solely supported by said truck for moving said bar angularly 95 relative to said trackway, and power operated means solely supported by said truck for moving the latter along said trackway to feed said bar longitudinally of the trackway.

110. In mining apparatus, the combination with a wheeled truck movable on a trackway, of cutter mechanism pivotally mounted thereon and comprising a cutter chain-carrying cutter bar adapted to swing across the end of the truck, and self-contained power operated mechanism supported solely by said truck for moving said bar angularly relative to said trackway while the truck is stationary thereon and reversely longitudinally relative to the trackway during cutting by moving said truck along said trackway.

111. In mining apparatus, the combination with a wheeled truck movable on a trackway, of cutter mechanism pivotally mounted thereon and disposable in fixed relation at acute 120 angles to the trackway, and self-contained power operated means supported on said truck for moving the latter along said trackway to move said bar when so disposed rectilinearly relative to the trackway, relatively 125 transversely in the same plane while said truck remains stationary on the trackway, and reversely rectilinearly by moving said truck along said trackway reversely to form a parallel ribbed horizontal kerf of a depth 130

substantially equal to the length of the bar and in a face in front of the end of the trackway.

112. In mining apparatus, the combination
5 with a wheeled truck movable on a trackway, of cutter mechanism pivotally mounted thereon and including a cutter chain-carrying cutter bar disposable in fixed relation at acute angles to the trackway, self-contained
10 power operated means supported on said truck for moving the bar when so disposed rectilinearly relative to the trackway, relatively transversely in the same plane, and reversely rectilinearly to form a parallel

ribbed horizontal kerf of a depth substantially equal to the length of the bar and in a face in front of the trackway, said truck being moved along said trackway during rectilinear movements of said bar and occupying a stationary position on said trackway when thus moved relatively transversely in the same plane, and means for varying the plane of operation of said bar.

In testimony whereof I have signed my name to this specification, on this 2nd day of 25 July, A. D. 1913.

EDMUND C. MORGAN.
